Primary Examiner — Messina L Smith*Assistant Examiner* — Aram Kwon(74) *Attorney, Agent, or Firm* — RMCK Law Group,
PLC(57) **CLAIM**

The ornamental design for a HiFi mixer, as shown and described.

DESCRIPTION

FIG. 1 is a perspective view of a HiFi mixer showing our new design;

FIG. 2 is a front side view of the HiFi mixer of FIG. 1;

FIG. 3 is a rear side view of the HiFi mixer of FIG. 1;

FIG. 4 is a top side view of the HiFi mixer of FIG. 1;

FIG. 5 is a bottom side view of the HiFi mixer of FIG. 1;

FIG. 6 is a left side view of the HiFi mixer of FIG. 1; and,

FIG. 7 is a right side view of the HiFi mixer of FIG. 1.

The broken line showing of a HiFi mixer is included for the purpose of illustrating portions of the HiFi mixer and forms no part of the claimed design.

1 Claim, 7 Drawing Sheets(56)
